UNITED STATES PATENT OFFICE

MARCUS C. HOPKINS, OF WASHINGTON, DISTRICT OF COLUMBIA, ASSIGNOR TO TITANAFRAM CORPORATION, OF JERSEY CITY, NEW JERSEY, A CORPORATION OF DELAWARE

LOUD-SPEAKER

Application filed January 7, 1927, Serial No. 159,553. Renewed September 28, 1929.

The present invention relates to loud speakers of the type disclosed in my copending application, Serial No. 77,033, filed December 22, 1925, as being suitable for use with radio receiving sets or as announeers for telephone and line wire circuits. The loud speaker disclosed in that application comprises a relatively light and stiff diaphragm or tympanum preferably conical in shape and a sound board or resonator having greater mass than that of the central diaphragm. The connection between the diaphragm and the resonator or sound board is such that the diaphragm will respond to relatively high sound frequencies and will effectively reproduce the high tones or sounds, and will also transmit relatively low frequencies through said connection to the sound board so that it will respond to the relatively low frequencies and will effectively 10 reproduce them. It is the principal object of the invention there disclosed and claimed to provide a highly efficient loud speaker capable of regenerating or reproducing sound waves directly in free air without distortion 15 as in a horn or other amplifying device, the sound so regenerated retaining substantially the same balance of high and low tones as the original sound from which the actuating force was derived.

20 The principal object of the present invention is to provide a loud speaker of the foregoing type having a resonator of corrugated board and by this term I intend to include products of the type now commonly used in 25 the manufacture of cartons and packing boxes, and comprising one or more plane sheets of cardboard reinforced and stiffened by one or more sheets of corrugated cardboard.

30 The selection of a material suitable for use as a sound board or resonator in a loud speaker of the type above identified is not an easy matter. The weight of the material is of 35 importance and must be coordinated to the 40 weight and size of the tympanum or dia-

phragm and to the power available for actuating that tympanum or diaphragm. The elasticity and flexibility of the sound board material are of importance, and the way in which its fibres are grouped and are secured to one another are also of importance. The wood sound board of my prior application, Serial No. 77,033 is admirably suitable for use in loud speakers of the larger size or where an adequate actuating force is readily available; whereas, for smaller sizes, that is to say, where the diameter of the rim does not exceed 24" I have found that a cork board gives excellent results as described and claimed in my copending application, Serial No. 124,667, filed January 24, 1926.

In a copending application, Serial No. 87,491, filed February 11, 1926, I have disclosed and claimed a loud speaker in which the sound board is formed of synthetic lumber. By the expression "synthetic lumber" I intend to include relatively rigid sheets or boards made from fibers that have been separated in part at least and then reassembled in a heterogeneous arrangement in a new assembly. I regard the sounding board of the present application as being a species of this "synthetic lumber" genus, but with the rigidity regulated and coordinated to the other parts of the speaker, not by varying the pressure applied to the fibers in the press while they are being assembled, but regulated by the thickness and density of the cardboard sheets which make up the present board and further regulated by the corrugated character of certain of the component sheets of the present board.

I have discovered that ordinary corrugated cardboard will serve my purpose well, for it has the advantage that it is cheap in cost, easy to shape into the desired form, is relatively resistant to moisture, is free from warping and will withstand rough treatment during shipment and in the hands of the ultimate user. Most important of all, it has

proper acoustical properties when assembled with a sound board or a paper cone to be actuated by a radio receiving set.

Further objects and advantages of the present invention will become clear from the following detailed description taken in conjunction with the accompanying drawings wherein;

Figure 1 is a front elevation;

10 Figure 2 is a vertical section of the loud speaker shown in Fig. 1;

Figure 3 is a rear elevation;

Figure 4 is a plan view; and

15 Figure 5 is a fragmentary section through the sound board showing its multi-ply structure.

In the drawings, the loud speaker comprises a conical diaphragm or tympanum 1 coupled to a vibratory resonator or sound board 2 by means of a flexible coupling or hinge shown in Fig. 3. The conical diaphragm 1 is preferably made of cover paper cut and folded to shape and glued on a radial seam. Near the outer edge of the cone thus formed the paper is creased and then folded up to form a forwardly flaring brim 3. This brim naturally assumes an angle to the plane of the base of the cone equal to the angle between the radial elements of the cone and that base. The outer edge portion of the brim 3 is preferably glued to the inner circular beveled edge of the resonator or sound board 2. The necessary beveling or tapering of the inner circular edge of the sound board as shown at 4 can readily be produced as a part of the punch press operation whereby the sounding board is stamped out of a flat panel. The inner edge portion of the brim 3 seats upon and is glued to the tapering surface thus formed. In gluing or cementing the brim to the beveled edge 4 it is important that a part of the brim be left free to form a hinge on which the cone may float. Thus, with the brim $\frac{3}{4}$ " wide the cemented portion may have a width of $\frac{1}{4}$ " more or less and the remainder of the brim may be left free to swing.

The resonator or sound board 2 in accordance with this invention is made of corrugated board and in the embodiment here illustrated that board is of the kind commonly used by makers of cartons and shipping cases. It comprises a plane front lamination 5, a plane rear lamination 6 and an interposed corrugated lamination 7 glued along its edges to the plane boards. The outer edge of the annular sound board thus formed can be bound with a ring or band 8 of paper or wood glued in place. The vibratory actuating force is applied to the apex of the conical diaphragm by means of a rod or wire 9 which is adapted to be maintained in fixed relation to the diaphragm by means of a set screw 10. The rod 9 may be actuated by electromagnetic mechanism housed in a casing 11. The casing 11 may be attached to a sup-

port or spider 12 which in turn may be affixed to the resonator or sound board by bolts 13.

The loud speaker may be conveniently supported by suspending it on cords attached to the spider at the eyes 14.

70 In constructing a loud speaker of this type I have found that excellent results are obtained by making the cone $15\frac{1}{2}$ " in diameter and the sound board approximately 24" in diameter. This makes the transverse width of the annular sound board approximately 4 $\frac{1}{2}$ ", but good results may be obtained by making the sound board of less or a greater width than this. It may properly have a thickness of about $\frac{1}{2}$ ". The periphery of the sound board can be square or octagonal or oval.

75 In this type of speaker the central conical diaphragm efficiently reproduces higher tones and perhaps some of the intermediate tones, while the surrounding resonator or sound board efficiently reproduces the lower or bass notes. I have discovered that with a resonator made of corrugated board the reproduction of the lower or bass notes is very true and faithful. With this cheap and easily obtained material, as with the more expensive materials described in my copending applications, the lower notes are not only reproduced with accuracy, but the tonal quality is good, and there is a proper balance between the high and low tones.

80 In a companion application, Serial No. 79,329, filed January 5, 1926, I have described and claimed a loud speaker having a sounding board made of balsa wood. Loud speakers thus equipped give good sound reproduction with good tonal quality and balance for large and for small sizes, but the sound boards are difficult to make, particularly if built up as a multiple-ply veneer. Balsa wood splinters and breaks in the ply cutting machines and the pieces fray at the edges during handling in the mill. Also the completed board is inclined to warp unless special expedients are resorted to for holding it in shape.

85 I claim:

1. A loud speaker comprising a conical diaphragm and a resonator of corrugated board arranged adjacent the diaphragm and adapted to be actuated thereby.

2. A loud speaker consisting essentially of a central diaphragm and a sound reproducing rim of corrugated board surrounding said diaphragm.

3. A loud speaker comprising a central conical diaphragm and a sound reproducing rim of corrugated board surrounding the diaphragm and connected thereto to permit the diaphragm to respond to relatively high frequencies and the sound reproducing rim to respond to relatively low frequencies.

4. A loud speaker comprising a relatively light and stiff diaphragm, an external cor-

- rugated sound board of greater mass than the diaphragm and a flexible coupling between the two adapted to permit the diaphragm to respond to relatively high frequencies and adapted to transmit the relatively low frequencies to the sound board.
5. A loud speaker comprising a central relatively light and stiff diaphragm, an external resonator of corrugated board having greater mass than the diaphragm and a flexible coupling between the two adapted to permit the central diaphragm to respond to relatively high frequencies and adapted to transmit the relatively low frequencies to said resonator.
10. 6. A loud speaker comprising a central, conical diaphragm, an external resonator of greater mass than said diaphragm and a flexible coupling between the two adapted to permit the conical diaphragm to respond to relatively high frequencies and adapted to transmit the relatively low frequencies to said resonator.
15. 7. A loud speaker comprising a central conical diaphragm, an external resonator of corrugated board and a connection between said diaphragm and said board adapted to permit the central diaphragm to respond to relatively high frequencies and adapted to transmit the relatively low frequencies to said board.
20. 8. A loud speaker comprising a central conical diaphragm, a corrugated board providing an annular flange or skirt extending radially beyond the conical diaphragm and a connection between the conical diaphragm and the board adapted to permit the conical diaphragm to respond to relatively high frequencies and adapted to transmit the relatively low frequencies to said board.
25. 9. A loud speaker comprising a central conical diaphragm having an integral forwardly flaring brim portion and a corrugated board providing a flange portion extending radially beyond the conical diaphragm, said forwardly flaring brim portion of the conical diaphragm being attached to said board.
30. 10. A loud speaker comprising a conical diaphragm provided with a peripheral corrugation forming a hinge portion and a corrugated board providing a flange or skirt portion extending radially beyond the conical diaphragm, said hinge portion being secured to said board.
35. 11. A loud speaker comprising a corrugated board and a conical diaphragm flexibly connected thereto so that a portion of said board extends radially beyond said conical diaphragm, the flexible connection between the conical diaphragm and the sound board being adapted to permit the conical diaphragm to respond to relatively high frequencies and being adapted to transmit the relatively low frequencies to said board.
40. 12. A loud speaker comprising a diaphragm and a sound board of corrugated board connected thereto and adapted to be actuated thereby.
45. 13. A loud speaker comprising a central conical diaphragm made of paper, an external corrugated board resonator, and a flexible connection between the two adapted to permit the conical diaphragm to respond to relatively high frequencies and adapted to transmit the relatively low frequencies to said board.
50. 14. A loud speaker comprising a corrugated board resonator having a central opening, a conical diaphragm mounted in said opening, actuating means for said conical diaphragm and means for supporting said actuating means comprising a support attached to said board and spanning the central opening thereof.
55. 15. A loud speaker comprising an annular flat corrugated board resonator having a circular central opening, a conical diaphragm having a circular periphery, said diaphragm being mounted in said opening, and a flexible coupling between said diaphragm and said board adapted to permit the diaphragm to respond to relatively high frequencies and adapted to transmit the relatively low frequencies to said resonator.
60. 16. A loud speaker comprising an annular corrugated board resonator having a central opening, the edge portion of which is provided with a tapering seat and a conical diaphragm mounted in said opening, said diaphragm having a forwardly flaring frustoconical brim portion secured to said resonator on said tapering seat.
65. 17. A loud speaker comprising a flat annular resonator made of corrugated board, said resonator having a central opening, the edge portion of which is provided with a tapering seat and a fibrous conical diaphragm mounted in said opening and having an integral forwardly projecting brim, a part of said brim being attached to the sound board at said tapering seat.
